UNITED STATES PATENT OFFICE.

WILLIAM HORNICH, OF NEWARK, NEW JERSEY, ASSIGNOR TO THALHEIMER BROTHERS, OF SAME PLACE.

BUTTON-MAKING MACHINE.

SPECIFICATION forming part of Letters Patent No. 340,442, dated April 20, 1886.

Application filed December 4, 1885. Serial No. 184,690. (No model.)

To all whom it may concern:

Be it known that I, WILLIAM HORNICH, a citizen of the United States, residing at Newark, in the county of Essex and State of New Jersey, have invented certain new and useful Improvements in Button-Making Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The invention herein described and claimed relates to improvements in dies employed especially in making cloth-covered buttons, in which two operations are necessary to form the completed button, one in which the metallic face and the cloth covering are brought together, and the other operation closing the covered face upon the back.

The invention has reference specially to an improved and automatically-acting device for holding the lower die immovable while the first operation is done.

The objects of the invention are to secure a positively-acting device by means of which a more perfect and uniform button is produced; to allow the hands of the operator to be unoccupied, except in adjusting the shells, cloth, &c., in the dies, her whole attention being given to that alone, and in consequence of which a much larger quantity of buttons are produced than are secured by the old mechanism; to enable a less skilled and cheaper class of operatives to be employed, and to enable the operator to bring more power to bear in stamping up the buttons.

40 The invention consists in the combination, with button-forming dies in which it is necessary to hold portions of the dies immovable during one operation and to release the same during another operation, of an automatically-acting device that will engage with said dies, or a portion thereof, during the one operation and withdraw therefrom during the other of said operations.

Dies acting as above described are illustrated in the drawings, and one form of the

automatic holding device is also shown therein.

In said drawings, Figure 1 is a side elevation of a button-forming machine to which my improvement is attached. Fig. 2, Sheet 2, is 55 a similar view of a portion of the machine, showing another operation thereof and of the automatic device. Fig. 3 is a vertical section of the automatic holding mechanism, taken longitudinally therethrough. Fig. 4 is a plan 60 of the said holding mechanism, and Fig. 5 is a perspective view of the slotted side. On Sheet 3, Fig. 6 is a vertical section of the machine shown in Fig. 1, illustrating the relation of the several parts thereof during the 65 first operation. Fig. 7 is a similar view illustrating the relation of the parts in the second operation, which is shown in Fig. 2. Fig. 8 is a plan of the cloth blank that forms the 70 face-covering. Fig. 9 is an elevation of the metallic face. Fig. 10 is a section of the united blank and face. Fig. 11 is an elevation of the button-back. Fig. 12 is a plan of the additional die or tool used in the second 75 operation. Fig. 13 is an elevation of the stamping-bar in said die, and Fig. 14 is a vertical section of the additional die and its enclosed stamping-bar.

Similar reference-letters indicate corresponding parts in each of the above-described figures, which are embodied in three sheets of drawings.

In the drawings, A indicates the upper die, B the lower die, C the frame of the machine, D the die-bed, and E the frame-bed.

The upper die, A, consists of a collar, a, a stamping-bar, a', and a spring, a², held between the collar and a nut, a³, the bar a' moving vertically through the collar down into the lower die during the first operation of 90 bringing the face-shell and cloth covering together. The lower die, B, consists of a collar, b, moving on and around the lower stamping-bar, b', and a spring, b².

In the first operation the cloth covering is 95 laid in the lower die, and the shell is inserted in the upper die on the end of the bar a', and as the dies impinge the collar a strikes the collar b of the lower die, and, both remaining stationary by means of the holding device, the 100

bar a' descends still farther into the collar b and forces the shell and cloth down upon the lower stamping bar, b' , as in Fig. 6. To hold the collars immovable and permit the stamping-bar to descend still farther is the office of the holding mechanism, which acts automatically as the upper die descends and engages with the lower die or the collar b thereon, as indicated in Fig. 1.

10 In the second operation, in which the completed button is made, the lower collar is necessarily free, so as to be depressed, to allow which the holding mechanism disengages itself from said collar automatically, as indicated in Fig. 2.

15 In forming the completed button the back is laid in the lower die, and an additional tool or die, F , is placed thereon, within which die F is a vertically-moving stamping-bar, f , (indicated by dotted lines in Fig. 2, and also in Figs. 7, 12, 13, and 14,) upon which the bar a' descends, and, forcing the collar b down upon the stamping-bar b' , the parts of the button are united, as indicated in Fig. 7.

20 The construction, arrangement, and particularly the operation of the button-forming mechanism, are thus briefly described to show the relation of the holding mechanism, which constitutes the prime feature of the invention.

25 The holding device illustrated in the drawings, and selected to indicate one of the forms of mechanism that may be devised to act automatically, consists of a reciprocating slide, G , moving in a suitably-constructed bed, g , and a spring, g' , which engages the end of said slide, and acts to force the slide from holding-contact with the lower die, as shown in Figs. 2 and 3. In the slide is formed a slot, g^2 , the 30 forward end of which nearest the dies is rounded or inclined, as Fig. 3 sets forth.

35 The device for causing the slide to engage with the lower die consists of a rod, H , the lower end of which is formed to enter the slot 40 in the slide, and, coming in contact with the rounded or inclined end of said slot, forces the slide toward the dies. The rod H is secured at its upper end to an arm, h , projecting from the slide J , moving vertically in the frame of 45 the machine, and is of such length that at the proper time, when the upper die descends, the said rod will force or push the slide under the shoulder b^3 of the collar b and prevent the depression of the same during the first operation 50 of uniting the face-shell and cloth covering of the button.

55 When the tool F is inserted between the dies, the extra length prevents the rod H from entering the slotted slide, and in consequence the collar b is free to move, as hereinbefore described, under the downward pressure of the upper die. The relation of the parts and position of the rod during this operation are indicated in Fig. 2.

60 Heretofore a spring-actuated lever has been employed to engage with the movable collar on the lower die during the first operation of

uniting the face-shell and covering; but during the second operation of uniting the face and back, in which the lower movable collar is 70 depressed, the spring-lever in use must be held away from the lower die by the hand, leaving but one hand free to insert the backs, and hindering the movements of operator in working the foot-lever. 75

In my improved device the holding mechanism is placed back of the dies and out of the way of the operator, and is entirely automatic in its action, enabling the operator to give her whole attention to placing the shells, cloth 80 covering, &c., in the dies, and her full power in working the foot-lever that operates the machine, thereby more firmly uniting the parts of the button together.

To operate the old lever quickly and place 85 the parts of the buttons in the dies properly requires considerable training and more than ordinary skill. By the improved construction of the holding mechanism no previous training is necessary to operate the dies, and 90 a much greater quantity of buttons are produced by cheaper and less skilled hands in a given time.

Having thus described my invention, I desire to claim the following:

95

1. In a button-forming machine, the combination, with the lower die, having a movable collar thereon, and the upper die, provided with a spring-actuated collar, and a stamping bar or die working through said spring-actuated collar, of mechanism constructed and adapted to engage automatically with and hold the said movable collar on the lower die immovable when the upper die is depressed and the said stamping-bar is forced 100 downward through the spring-actuated collar into the lower movable collar, for the purposes set forth.

2. In a button-forming machine, the combination, with the lower die, having a movable collar thereon, and the upper die, provided with a spring-actuated collar, and a stamping bar or die working through said spring-actuated collar, of a reciprocating slide, and mechanism for causing said slide to 110 engage with the said movable collar on the lower die and hold the same immovable when the dies impinge, substantially as and for the purpose set forth.

3. In a button-forming machine, the combination, with the lower die, having a movable collar thereon, and the upper die, provided with a spring-actuated collar, and a stamping bar or die working through said collar, of mechanism for holding the collar on 120 the lower die immovable when the dies impinge, consisting of a reciprocating slide having a slot therein, the end of which nearest the dies is inclined or beveled, a rod connected and moving with the upper die and engaging 125 with the beveled end of the slot in its downward movement, and a repressing-spring, all said parts being arranged and operating substantially as and for the purposes set forth.

4. In a button-making machine, in combination, an upper die consisting, essentially, of a stamping-bar, a spring-actuated collar and a spring, a lower die consisting of a movable collar, a stamping-bar on which said collar moves, and a spring engaging with said collar, a slotted reciprocating slide, a repressing-spring engaging with said slide, a rod or arm connected and moving with the upper die, and a button-forming tool adapted to be inserted between the upper and lower dies, and of such

a length as to prevent the rod connected with the upper die from engaging with the reciprocating slide, for the purposes set forth.

In testimony that I claim the foregoing I 15 have hereunto set my hand this 21st day of November, 1885.

WILLIAM HORNICH.
